UNITED STATES PATENT OFFICE.

JOSEPH M. OUGH, OF SAN FRANCISCO, CALIFORNIA, AND MONTGOMERY WADDELL, OF NEW YORK, N. Y.

VARIABLE-SPEED GEAR.

SPECIFICATION forming part of Letters Patent No. 716,928, dated December 30, 1902.

Application filed September 27, 1900. Serial No. 31,330. (No model.)

To all whom it may concern:

Be it known that we, JOSEPH M. OUGH, a citizen of the United States, residing in the city of San Francisco, in the county of San Francisco and State of California, and MONTGOMERY WADDELL, a subject of the Queen of Great Britain, residing in the city, county, and State of New York, have jointly invented a certain new and useful Improvement in Variable-Speed Gear, of which the following is a specification.

Our present invention relates particularly to improvements in planetary gears adapted to propulsion of vehicles wherein a plurality of speeds is desirable for moving forward and one speed for reverse movement.

The principal object of our invention is the provision of means whereby a slow backward movement may be produced in combination with means for suitably-graduated forward movements.

Our invention is illustrated in the accompanying drawings, wherein—

Figure 1 is a longitudinal vertical section of our device. Fig. 2 is an end view thereof; and Fig. 3 is a transverse section, one half upon the line 3 3 of Fig. 1 and the other half on the line 4 4.

The driving axle or shaft 1 is supplied with two fast driving-pinions 2 and 3, between which a two-part transmitting-sleeve 4 turns loosely upon said shaft. The sprocket 5 or other driven part is fixed to said sleeve. Upon one side the two-part sleeve 4 is expanded into a bearing-disk 6, while the opposite extremity of said sleeve is expanded into a drum 7, provided with an internal gear. An auxiliary bearing-disk 8 turns loosely upon the shaft 1, and an axis 9 has its two extremities journaled in the respective disks 6 and 8. Fast to the axis 9 are two orbital pinions 10 and 11, the smaller of which engages with the pinion 2 and the larger of which overlaps said pinion between it and the auxiliary disk 8. Of course these two may be considered as one pinion having two sections of different diameters. Engaging with the pinions 10 and 11 are two internal gears within drums 12 13, as shown. Either of these drums may be held fixed by means of the strap-brakes 14 15.

The drum 13 is considerably wider than the

pinion 11, and within the portion of said drum which is outside of the disk 8 we employ an expansion-grip composed of an elastic band 16, to one end of which is pivoted the lever 17, whose short end by pressing upon the opposite end of the band 16 acts to expand it and grip the drum 13, thus locking it to the shaft 1. The outer end of the lever 17 bears upon the slidable sleeve 18, which is beveled at its inner end, so that when said sleeve is pushed inward and the lever rides upon the cylindrical portion of said sleeve the lever acts to expand the gripping-band 16, and when the sleeve 18 is pulled out the gripping pressure is released by movement of the end of the lever toward the shaft 1.

The second driving-pinion 3 lies within the drum 7, whose internal gear engages with a pinion 19, itself engaging with pinion 3 and turning upon or with the shaft 20, carried in a bearing on the reversing-drum 21. This drum may be held fixed by means of the strap-brake or its equivalent for reversing the movement of the sprocket 5.

To start our gear at the low speed, the brake 14 is first applied. The pinion 2 then forces the orbital pinion 10 to roll around within the internal gear in the drum 12, and the transmitting-sleeve and sprocket 4 5 are thus forced to turn in the same direction as the shaft 1, but much more slowly. Upon releasing the brake 14 and applying the brake 15 the same reaction takes place between pinion 11 and the gear within the drum 13; but on account of the greater size of the pinion in relation to its surrounding drum the forward movement now produced in the transmitting-sleeve 4 and sprocket 5 is increased, being still less than that of the shaft 1.

Full speed is produced by locking together the shaft 1 and the drum 13, whereby the pinions 10 11 are prevented from turning and the sleeve 4 moves with the same speed as the shaft 1.

Upon releasing all other brakes, but applying the brake 22, the pinion 19 is held in a fixed position, and through it the driving-pinion 3 acts to turn the drum 7, which carries with it the transmitting-sleeve. This movement is opposed in direction to that of the shaft 1 and much slower. This slow speed

is obviously advantageous for backing vehicles.

In this specification we have mentioned the pinions in the singular, but, as shown in Fig. 3, we preferably use a number of these pinions in symmetrical positions around the driving-shaft. The number actually shown is of course not essential.

What we claim is—

- 10 In a reversible planetary gearing, a driving-shaft, a driving-pinion fast thereon for forward movement and a driving-pinion fast thereon for backward movement, and a two-part transmitting-sleeve loose on said shaft 15 between said pinions, orbital gears carried

by one of said transmitting parts on one side over one driving-pinion and an internal gear carried by the other transmitting part on the opposite side over the other driving-pinion; in combination with a driven element keyed 20 to both parts of said sleeve and means whereby each part of said sleeve may be independently brought into operative relation with its corresponding driving-pinion.

JOSEPH M. OUGH.
MONTGOMERY WADDELL.
